UNITED STATES PATENT OFFICE

159,912

MOTION-PICTURE PROJECTOR

Frank Lustig, Chicago, Ill., assignor to Revere
Camera Company, Chicago, Ill., a corporation
of Delaware

Application March 6, 1950, Serial No. 8,337

Term of patent 14 years

(Cl. D61—1)

To all whom it may concern:

Be it known that I, Frank Lustig, a citizen of the United States, residing at Chicago, State of Illinois, have invented a new, original, and ornamental Design for a Motion-Picture Projector, of which the following is a specification, reference being had to the accompanying drawings, forming a part hereof.

Fig. 1 is a side elevational view of the motion-picture projector, showing the essential features of my design in the base which is illustrated in full lines, the broken lines shown in this figure being omitted from the other figures for the convenience of illustration;

Fig. 2 is a rear elevational view of the base only;

Fig. 3 is a front elevational view, and

Fig. 4 is a top plan view thereof.

I claim:

The ornamental design for a motion-picture projector, substantially as shown and described.

FRANK LUSTIG.
